UNITED STATES PATENT OFFICE

1,970,491

PRINTING PRESS

Curtis S. Crafts, Oak Park, Ill., assignor to The
Gess Printing Press Co., Chicago, Ill., a corpo-
ration of Illinois

Application July 10, 1931, Serial No. 549,950

5 Claims. (Cl. 270—5)

My invention relates to printing presses and it has for its object the provision of a new and improved form and arrangement of means for driving the several press and folder units whereby a smoother and more even operation may be attained than heretofore, and whereby there shall be a very great flexibility in the matter of the connection of the several units so that a great variety of products may be produced.

5 It is one of the objects of my invention to provide an improved arrangement whereby the several units of a press may be driven by a like number of motors, with each motor adapted particularly for the operation of its own individual unit to best advantage at the predetermined desired speed by positively-acting driving connections between the motor and the unit, and with the parts arranged in an improved manner whereby the several units may be 10 grouped in a variety of ways and with the motors arranged in such manner that they can conveniently and readily be grouped in the same way, the motors being connected in such manner mechanically in the various groupings as to cause them to operate smoothly together at all 15 times.

It is one of the objects of my invention to arrange my improved press and driving means in such manner as to minimize the effect of vibration, whereby the press may be run at high speeds without undue stresses and strains on the parts. To this end, it is one of my objects to provide an improved arrangement whereby the motors shall be mounted as nearly as is practical independently of the frame-work which supports the printing cylinders and associated cooperating parts. It is another object of my invention to provide an improved arrangement of the motors whereby the driving connections between the motors and the units shall interfere as little as possible with the handling of the press and the webs and as little as possible with the adjustments and other operations in connection with the inking mechanisms. To this 20 end, it is one of my objects to provide for the location of the motors at a lower level than that of the press units, leaving the entire press floor space available for the control of the press units and leaving the space above the press open so far as possible for the manipulation of the webs of paper in preparing the press for operation, and so as to leave room above the form and impression cylinders for any auxiliary press parts as may be desired for operation upon selected 25 ones of the webs printed by the main press.

It is another object of my invention to improve printing presses in sundry details hereinafter pointed out. The preferred means by which I have accomplished my several objects are illustrated in the drawing and are hereinafter 60 specifically described. That which I believe to be new and desire to cover by Letters Patent is set forth in the claims.

In the drawing, which is more or less diagrammatic throughout,

65 Fig. 1 is a side view of a printing press embodying one form of my improvements, and showing the driving means for the press units located below the press;

Fig. 2 is a view of one of the press units as 70 shown in Fig. 1 but upon an enlarged scale with additional parts illustrated; and

Fig. 3 is a view of a fragmentary portion of my improved press as seen at the far end of the press unit shown in Fig. 2, as seen substantially 75 at the line 3—3 of said Fig. 2.

Referring now to the drawing, in which corresponding parts are indicated by the same reference characters, 10 indicates a heavy framework, upon which unit frames 11, 12, 13, 14 and 15 are mounted in alignment with each other in the form of construction as shown in Fig. 1, the several unit frames being joined together at their upper end portions by a heavy frame bar 16. As will be readily appreciated, the unit frames 11, 13 and 14 comprise portions of press units each of which is provided with a pair of printing couples adapted for perfecting a web 17. The unit frames 12 and 15 comprise portions of folder units of any approved type, each of said folder units being illustrated with a web 18 in position therein. The press units 11, 13 and 14 and the press units 12 and 15 are designed to be of any approved type.

90 Each of the press units 11, 13 and 14 in the 95 form shown in my drawing is designed to be of the type shown in Fig. 2, comprising impression cylinders 19 and 20, form cylinders 21 and 22, inking drums 23, 24, 25 and 26, numerous ink rollers 27, ink fountains 28 and ductor rollers 29, 100 together with the ordinary well-known actuating means for such parts. In the construction shown, each of the form cylinders 21 and 22 is supported by a shaft 30, being driven by bevel gears 31 and 32 mounted upon said shafts 30 and upon 105 a shaft 33 carried by bearing brackets 34 substantially opposite the ends of the form and impression cylinders. As is clearly shown in Fig. 3, the impression cylinder and form cylinder of each printing couple of the press unit are con- 110

nected by means of intermeshing gears 35 and 36 at the far side of the press as shown in Fig. 2.

Upon the frame 37, preferably comprising a floor structure, I have provided individual motors 38, 39, 40, 41 and 42 for the several units 11, 12, 13, 14 and 15 as above described. Each of said motors is connected at one end by means of a coupling 43 with a shaft section 44, all of said motors being in alignment with each other 10 underneath the press comprising the sections 11, 12, 13, 14 and 15. Each shaft section 44 is supported by standards 45 at each end portion thereof. Each of said shafts 44 is connected with the motor next adjacent thereto at the 15 left in said Fig. 1 by means of a clutch 46, each of said clutches being of any approved type whereby the motors and shaft sections may be releasably connected together. Upon each shaft section 44, I have provided a clutch 47 for 20 releasably connecting such shaft section with a sprocket gear loosely mounted upon such shaft section, such loosely mounted sprocket gear being connected by means of a sprocket chain with an oppositely disposed sprocket gear fixedly 25 mounted upon the corresponding units 11, 12, 13, 14 and 15 of the press. In the construction shown, the five sprocket chains referred to are indicated respectively by the numerals 48, 49, 50, 51 and 52. In the construction shown, the 30 sprocket gears at the upper ends of the sprocket chains 48, 50 and 51 are mounted upon the shafts 33 of the press units, while the sprocket gears for the folder units 12 and 15 are mounted upon horizontally disposed shafts 53 forming parts of 35 the operating mechanisms of said units.

By the use of my improved construction as illustrated and as above described, an individual motor is provided for each of the units of the press, such motor being of a type adapted for 40 driving the corresponding unit at the desired speed of rotation. When a single unit is to be driven alone, the clutches 46 at opposite sides of the corresponding motor are disconnected, while the clutch 47 of the corresponding motor 45 is thrown into operation. When the entire press is to be operated except for a single unit to be left idle, all of the clutches 46 and 47 would be connected except for the clutch 47 of the idle unit. As will be readily understood, my improved 50 arrangement provides for a very wide range of different connections and groupings of the several motors and press units.

By reason of my improved construction, the 55 operation of my improved press is made very smooth and even, since any combination of units is operated at all times by a corresponding group of motors designed specifically for the operation of such grouping of units. By reason of having the motors located on a frame-work independ- 60 ently of the frame which supports the press units, the vibration produced by the operation of the motors at high speed is transmitted very little if any at all to the press, whereby operation at high speeds is rendered much less objectionable. 65 By reason of the location of the motors below the press rather than at some other location, the driving connections between the motors and the press units are kept out of the way, leaving the entire press floor available for the operators, 70 and leaving the entire space above the press available for use for locating auxiliary printing and web handling mechanism if desired. By the use of chain driving means from the motor direct to the unit, the number of meshing connections 75 between the cylinders and the motors is very

materially cut down as compared with other types of driving connections as heretofore employed, serving thus to keep the cylinders much better in synchronism with each other, and serving materially to cut down the likelihood that a web shall be torn in operation of the press at high speeds. 80

While I prefer to employ the form of construction as shown in my drawing and as above described, it will be understood that my invention is not limited thereto except so far as the claims may be so limited by the prior art. 85

I claim:—

1. In a printing press, the combination of a frame, a plurality of press units mounted on said frame in alignment with each other therealong, a folder unit mounted on said frame in alignment with said press units, individual motors for the several units located below the units with their drive shafts in alignment with each other, auxiliary shafts between each two adjacent motor shafts and in alignment with said motor shafts, a supporting bearing for each of said auxiliary shafts at each end portion thereof, couplings between each of said auxiliary shafts and the motor shaft at one end thereof, clutches for connecting each of said auxiliary shafts with the motor shaft at the opposite end, and endless belt driving connections extending downwardly from each of said units and connected at its lower end portion with one of said auxiliary shafts. 90

2. In a printing press, the combination of a frame, a plurality of press units mounted on said frame in alignment with each other therealong, a folder unit mounted on said frame in alignment with said press units, individual motors for the several units located below the units with their drive shafts in alignment with each other, auxiliary shafts between each two adjacent motor shafts and in alignment with said motor shafts, a supporting bearing for each of said auxiliary shafts at each end portion thereof, couplings between each of said auxiliary shafts and the motor shaft at one end thereof, clutches for connecting each of said auxiliary shafts with the motor shaft at the opposite end, and endless belt driving connections extending downwardly from each of said units and connected at its lower end portion with one of said auxiliary shafts. 100

3. In a printing press, the combination of a frame, a plurality of press units mounted on said frame in alignment with each other therealong, a folder unit mounted on said frame in alignment with said press units, individual motors for the several units located below the units with their drive shafts in alignment with each other, auxiliary shafts between each two adjacent motor shafts and in alignment with said motor shafts, a supporting bearing for each of said auxiliary shafts at each end portion thereof, couplings between each of said auxiliary shafts and the motor shaft at one end thereof, clutches for connecting each of said auxiliary shafts with the motor shaft at the opposite end, and endless belt driving connections extending downwardly from each of said units and connected at its lower end portion with one of said auxiliary shafts. 110

4. In a printing press, the combination of a frame, a plurality of press units mounted on said frame in alignment with each other therealong, a folder unit mounted on said frame in alignment with said press units, individual motors for the several units located below the units with their drive shafts in alignment with each other, auxiliary shafts between each two adjacent motor shafts and in alignment with said motor shafts, a supporting bearing for each of said auxiliary shafts at each end portion thereof, couplings between each of said auxiliary shafts and the motor shaft at one end thereof, clutches for connecting each of said auxiliary shafts with the motor shaft at the opposite end, and endless belt driving connections extending downwardly from each of said units and connected at its lower end portion with one of said auxiliary shafts. 120

5. In a printing press, the combination of a frame, a plurality of press units mounted on said frame in alignment with each other therealong, a folder unit mounted on said frame in alignment with said press units, individual motors for the several units located below the units with their drive shafts in alignment with each other, auxiliary shafts between each two adjacent motor shafts and in alignment with said motor shafts, a supporting bearing for each of said auxiliary shafts at each end portion thereof, couplings between each of said auxiliary shafts and the motor shaft at one end thereof, clutches for connecting each of said auxiliary shafts with the motor shaft at the opposite end, and endless belt driving connections extending downwardly from each of said units and connected at its lower end portion with one of said auxiliary shafts. 130

6. In a printing press, the combination of a frame, a plurality of press units mounted on said frame in alignment with each other therealong, a folder unit mounted on said frame in alignment with said press units, individual motors for the several units located below the units with their drive shafts in alignment with each other, auxiliary shafts between each two adjacent motor shafts and in alignment with said motor shafts, a supporting bearing for each of said auxiliary shafts at each end portion thereof, couplings between each of said auxiliary shafts and the motor shaft at one end thereof, clutches for connecting each of said auxiliary shafts with the motor shaft at the opposite end, and endless belt driving connections extending downwardly from each of said units and connected at its lower end portion with one of said auxiliary shafts. 140

7. In a printing press, the combination of a frame, a plurality of press units mounted on said frame in alignment with each other therealong, a folder unit mounted on said frame in alignment with said press units, individual motors for the several units located below the units with their drive shafts in alignment with each other, auxiliary shafts between each two adjacent motor shafts and in alignment with said motor shafts, a supporting bearing for each of said auxiliary shafts at each end portion thereof, couplings between each of said auxiliary shafts and the motor shaft at one end thereof, clutches for connecting each of said auxiliary shafts with the motor shaft at the opposite end, and endless belt driving connections extending downwardly from each of said units and connected at its lower end portion with one of said auxiliary shafts. 150

on said base frame, a pair of printing couples comprising a press unit mounted on each of said unit frames, a motor for each of said units supported below the unit and each adapted for driving its particular unit at the prescribed speed of rotation independently of the other units, positively-acting driving connections between each motor and its unit in the form of an endless chain operating in a plane extending transversely of 5 said base frame, and means connecting said motors serving with each motor driving its particular unit to keep the motors in timed relation for synchronous operation of the several units.

10 5. In a printing press, the combination of a base frame, a plurality of unit frames mounted on said base frame, a pair of printing couples comprising a press unit mounted on each of said unit frames, a motor for each of said units supported below the unit independently of the unit frame 15 and each adapted for driving its particular unit

at the prescribed speed of rotation independently of the other units, shaft means extending longitudinally of said base frame serving to connect said motors in a series for causing the motors to rotate in timed relation, a sprocket gear fixedly mounted on said shaft means adjacent to each of said motors so as to rotate with said motor, a sprocket gear rotatably mounted on each of said unit frames substantially opposite the printing couples in the same plane as that in which the first named sprocket gear for said unit is rotated, means for driving each of said printing couples from the sprocket gear opposite thereto, and positively-acting endless chain means connecting the sprocket gear of each of said units with the sprocket gear of the corresponding motor serving to cause said units to operate in synchronism with each unit driven by its individual motor. 20
